DUDLEY W. TRAVIS, OF ENFIELD, NEW YORK.

Letters Patent No. 85,189, dated December 22, 1868.

IMPROVEMENT IN CORN-CULTIVATORS.

The Schedule referred to in these Letters Patent and making part of the same.

To all whom it may concern:

Be it known that I, DUDLEY W. TRAVIS, of Enfield, Tompkins county, New York, have invented an Improved Corn-Cultivator; and I do hereby declare that the following is a full and accurate description thereof, reference being had to the accompanying drawings, and to the letters thereon.

Figure 1 is a side elevation of my corn-cultivator; Figure 2, a front elevation; and

Figure 3, a top view of the front hinge-plate, from which the traction is made on the cultivator-frame.

Figure 4 is a view of the adjustable attachment of the plows and hoes to the posts or standards H and I.

My object is to make a two-horse corn-cultivator, in such a manner as to cultivate each side of the row of corn, with each horse and each wheel in between the rows; and

My invention relates, mainly, to the frame for the plows or hoes, and to the traction of the frame.

In fig. 1, A A A are the thills, wheels, and seat for the driver, constituting the carriage; and

B, a stout cross-bar, with a strong metallic plate, C, on it, the two firmly braced to the tongue or thill of the carriage, just behind the horses; and

D is a four-parted frame-work, hung by the hinges E to the piece B, and held together in the rear by the cross-bars F and G; and

H and I are the posts that hold the plows or hoes at their lower ends, and are fast to the cross-bars; and J J are stout iron braces for these plow or hoe-posts; and

K and L are the hoes or plows at their ends; and M is a hand-lever, that raises the hoes, or plows, or cultivators out of the ground; while, by the set-screws N, the front hoes or cultivators are set to any required depth, as well as to suit the team, and the lever is, at option, held by the lock O.

In fig. 2, the same letters show the same parts, except that P P are two other braces of the cultivator-frame.

In fig. 3, the same parts are shown by the same letters as in figs. 1 and 2.

The uses and advantages of my invention are apparent to those skilled in the art to which it appertains.

Claim.

The herein-described mode of adjusting the plows and hoes, in combination with the posts or standards H and I, bars F G, and frames D, when the whole is constructed and arranged substantially in the manner shown and described, and for the purpose set forth.
